PERPETUAL CALENDAR

Philip L. Mayhew, Modesto, Calif.

Application January 24, 1944, Serial No. 519,440

1 Claim. (Cl. 40—109)

This invention relates to a perpetual calendar, my principal object being to provide a calendar of this type so arranged that the correct monthly calendar arrangement for any one of a great many years may be easily obtained by simply shifting a slide panel.

Another object is to provide an index arrangement to determine the shifting of the panel so that no calculations on the part of the operator are necessary in finding the calendar for any desired year.

A further object of the invention is to produce a simple and inexpensive device, and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Figure 1 is an elevation of my improved calendar showing the index face thereof.

Figure 2 is a transverse section on the line 2—2 of Fig. 1.

Figure 3 is an elevation of the calendar showing the calendar side thereof, partly broken out.

Figure 4 is an elevation of the slide, detached.

Referring now more particularly to the characters of reference on the drawings, the device comprises a rectangular body 1 which, for convenience of manufacture, may be made up of a number of panels arranged as laminations suitably secured together about their periphery.

One face panel 2 is provided with a rectangular window 3 exposing one face portion of the adjacent panel 4, the exposed face of said panel having a list of years printed thereon, as at 5, with an index symbol 6 after each year, seven different symbols being sufficient to carry the calendar over any period of time. The list of standard or normal years is preferably separated from the list of leap years, as shown.

On the back of the panel 4 are printed two sets of monthly calendars suitably spaced and arranged in rows in vertically spaced relation as at 7 and 8; the set 7 being for normal or standard years and the set 8 for leap years.

As shown in Fig. 3, each calendar set 7 or 8 consists of such a pre-calculated arrangement of numbers in thirteen vertical rows that if any six vertical rows from either or both ends of the calendar are covered, the seven remaining rows will correctly denote the days of a month in proper

sequence or conventional order. All the calendars 7 and 8 are of course figured so that from month to month they will read in proper order when the corresponding rows of different calendars are covered or blocked off.

In order to thus cover six selected vertical rows of all the calendars simultaneously, a horizontally slideable panel 9 is mounted in the body back of the panel 4. Assuming that each set of calendars 10 7, and which consists of twelve monthly units, are arranged in vertical rows of four months each, the panel is provided with horizontally spaced windows 10, each the height of all four calendar units and of a width equal to seven vertical rows 15 of numbers on each unit. Similar windows 11 are provided in the panel 9 to align with the units of the calendar set 8. The vertical division webs 12 between the windows 10 and 11 are marked along one edge with symbols indicating the months of 20 the year, as at 13, while the horizontal division webs 14 between the windows 10 and 11 are marked to indicate the days of the week, as at 15.

Another vertical slide panel 16 is mounted in the body to cover either the top or bottom portion of the panel 9 and the corresponding exposed calendar, so that only the calendar set 7 or the calendar set 8 at a time are visible.

The slide 16 is disposed between a panel 17 and the back panel 18 of the body, said panels 30 17 and 18 having windows 19 therein of sufficient size to expose all the calendars and the adjacent portions of the slide panel 9. The slide 16 may have a finger engaging element 20 on its back face for manipulating the same, or any other 35 suitable control means may be provided.

In order to slide the panel 9, the same is provided on top of the body with a finger piece 21. In order to be able to readily set the panel 9 for any desired year the panel 1 is provided on its 40 outer face with a horizontal row of stops, such as indentations 22, each marked with one of the indicia 6, as shown at 23, the stops being spaced horizontally the same as the horizontal spacing of the adjacent vertical rows of figures on the calendars 7 or 8. A pointer 24 depends from the finger-piece 21 and overlaps the stops 22, having an element 25 to engage any stop in cooperating relation.

The position of the slide 9 relative to the calendars thus obtained is, by reason of the indicia 23, co-related with any listed year having the corresponding indicia, which is of course previously determined to be correct for the calendar then exposed by the slide 9.

In the illustration shown for instance, it is

assumed that the user desires to inspect the calendar for the year 1938. Noting from the index that this year bears the symbol G, the operator shifts the panel 9 so that the pointer 24 aligns with the symbol G along the row of stops and then turns the body over. The calendar then exposed will be the correct one for 1938. The same setting of the slide 9 is obtained for certain other years, as for instance the leap year 1944 (as will be evident by an inspection of the index listing), which has the symbol G opposite that year. In this case, however, the user on turning the body over first raises the slide 16 to expose the leap-year calendar set 8.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

A perpetual calendar including a panel having imprinted thereon monthly calendar units each

unit consisting of thirteen vertical horizontally spaced rows of figures denoting the days of a month and arranged so that any seven consecutive rows of figures will include the days of a single month arranged in predetermined order, a listing of years also being associated with the panel and each year in the list having an identifying symbol, corresponding symbols associated with the panel adjacent one edge thereof, a horizontally shiftable slide mounted on the panel and having windows spaced apart to correspond to the spacing of the calendar units, the width of the openings being such as to uncover only seven vertical rows of figures in the calendar unit at a time, the symbols associated with the panel being spaced apart substantially the same distance as the spacing between the respective vertical rows of figures, a finger piece attached to one edge of the slide and extending outside of and along the edge of the panel adjacent which the year symbols are disposed, a pointer on the finger piece and overhanging the edge of the panel to a point adjacent said symbols, the panel being provided with an indentation adjacent each symbol and the pointer including an element to frictionally engage such indentations as the pointer is moved with the slide.

PHILIP L. MAYHEW.
